UNITED STATES PATENT OFFICE

147,791

DESIGN FOR AN AIRPLANE

Walter C. Jamouneau, Lock Haven, Pa., assignor
to Piper Aircraft Corporation, Lock Haven, Pa.,
a corporation of Pennsylvania

Application August 30, 1945, Serial No. 121,735

Term of patent 14 years

(Cl. D71—1)

To all whom it may concern:

Be it known that I, Walter C. Jamouneau, a citizen of the United States, residing at Lock Haven, county of Clinton, State of Pennsylvania, have invented a new, original, and ornamental Design for an Airplane, of which the following is a specification, reference being had to the accompanying drawings, forming a part thereof.

Fig. 1 is a perspective view of an airplane showing my new design,

Fig. 2 is a plan view,

Fig. 3 is a side view, and

Fig. 4 is a front view.

I claim:

The ornamental design for an airplane, as shown.

WALTER C. JAMOUNEAU.
